DESK STAND FOR A HAND TELEPHONE

Gerald A. Berting, Galion, Ohio, John A. Dienner, Evanston, Ill., and James M. Robinson, Galion, Ohio, assignors to North Electric Company, a corporation of Ohio

Application September 24, 1953, Serial No. 26,948

Term of patent 14 years

(Cl. D26—14)

Figure 1 is a perspective view of a desk stand for a hand telephone, showing our new design;

Figure 2 is a side elevational view thereof;

Figure 3 is a top plan view thereof; and

Figure 4 is a rear elevational view thereof.

The dominant features of our design reside in those portions shown in full lines.

We claim:

The ornamental design for a desk stand for a hand telephone, as shown and described.
